UNITED STATES PATENT OFFICE.

JAMES B. VERNON, OF PRINCETON, WEST VIRGINIA.

AUTOMATIC STARTING AND EQUALIZING PRESSURE-VALVE FOR COMPOUND ENGINES.

1,352,853.

Specification of Letters Patent. Patented Sept. 14, 1920.

Application filed August 21, 1917. Serial No. 187,459.

To all whom it may concern:

Be it known that I, JAMES B. VERNON, a citizen of the United States, residing at Princeton, in the county of Mercer and State 5 of West Virginia, have invented certain new and useful Improvements in Automatic Starting and Equalizing Pressure-Valves for Compound Engines, of which the following is a specification.

10 My invention relates to new and useful improvements in valves and has as its primary object the provision of an automatic starting and equalizing pressure valve for compound engines of locomotives.

15 It has long been recognized that in the employment of compound engines, such as those of the Mallet type on locomotives, some means for admitting live steam to the low pressure engine or cylinder is desirable 20 inasmuch as a train when starting requires the greatest possible engine power. Obviously, when starting the locomotive it is necessary with the previously employed arrangements that the high pressure engine or 25 cylinder operate through several revolutions of the drivers before any appreciable amount of steam is supplied to the low pressure engine, this being due to the fact that there are such rapid condensations of the steam 30 that the exhaust steam from the high pressure engine is of little benefit until the locomotive is well under way.

Because of this failure to supply steam to the low pressure cylinder, undesirable 35 slipping of the high pressure engine is caused as the low pressure engine has no pressure to build up against the high pressure engine and when the high pressure engine slips the low pressure engine will also 40 slip. Furthermore, when the low pressure engine slips, on account of difference in volume of the cylinders of the two engines, the steam is exhausted faster than the high pressure engine can supply it, which, consequently, reduces back pressure on the high 45 pressure engine and makes it liable to slipping.

One of the chief objects of my present invention is the provision of a valve which 50 will overcome these defects by providing live steam to the low engine at the time the locomotive is being started and which will continue to supply live steam to such engine until the exhaust steam from the high pressure 55 sure engine passing to the low pressure en-

gine is sufficient to create the proper ratio of pressure to the engine.

In this connection, a further object of my invention resides in constructing the valve so that it will be automatic in its action and 60 so that if, for any reason, the steam pressure being supplied falls too low while the engine is running, it will automatically open to build up pressure in the low pressure engine.

65

A still further object which I have in view is the provision of means by which the valve may be opened at any desired time by the engineer.

In addition to accomplishing these objects, I also provide a structure which is simple, economical to manufacture and install and durable and efficient in use.

In the drawings:

Figure 1 is a central vertical sectional view taken through the valve,

Fig. 2 is a transverse sectional view taken on the line 2—2 of Fig. 1 looking in the direction of the arrows,

Fig. 3 is a fragmentary perspective view 80 illustrating the application of the valve.

Fig. 4 is a view illustrating a locomotive of the compound type to which the invention is applied.

Corresponding and like parts are referred 85 to in the following description and indicated in all the views of the drawings by the same reference characters.

In order to insure a clear and accurate understanding of my invention and its operation, I will first describe the construction of the valve, then its application in connection with the engine and then its operation.

The main body or casing of the valve indicated in general by the reference letter A 95 includes an intermediate section 10 and terminal sections 11 and 12. The intermediate section is formed in one side with an opening surrounded by an internally threaded nipple 13 and at its top is reduced and externally threaded, as shown at 14, for engagement with the lower end of the terminal section 11. This reducing of the top of the section 10 provides a stop shoulder 15 which insures a close joint between the two sections. A spider 16 extends across the intermediate section 10 with its central portion slightly below the level of the center of the passage through the nipple 13 which is the outlet passage of the valve and serves 105 110

as a guide for the stem 17 of the valve proper 18 which is adapted to coöperate with a frusto-conical valve seat 19 formed in the upper end of the intermediate section 10 of the casing. This valve stem 17 projects upwardly beyond the valve and has a reduced portion 20 which operates in a spider 21 formed across the terminal section 11. A helical spring 22 surrounds the valve stem bearing at one end against the spider 16 and at its opposite end against the lower face of the valve 18 which is formed with a central boss 23 to centralize the spring 22. This spring 22, of course, acts to maintain the valve in open position and the extent to which the valve may open is limited by the stop shoulder 24 at the juncture of the valve stem and its reduced terminal 20. The upper end of the terminal section 11 is formed with an inlet opening surrounded by an internally threaded nipple 25.

The lower end of the intermediate section is internally threaded to receive the threaded upper end 26 of the lower terminal section 12 which is threaded for engagement with the section 10 and which, adjacent its threaded portion, is provided with a stop flange 27 to insure a close joint between the sections. The outer or peripheral face of this flange is formed with flattened faces to receive a wrench or other suitable tool in order that it may be readily applied. The lower end of the terminal section 12 is internally threaded to receive a plug cap 28 and adjacent the lower end, the section 12 is formed with a lateral internally threaded opening 29. Interiorly, the casing section 12 is formed with an upper axial cylindrical chamber 30 opening into a lower axial cylindrical chamber 31, of somewhat greater diameter.

Mounted within these chambers is a plunger 32 which, intermediate the length of the chamber 31, is reduced to receive a plurality of washers 33 each of which has its upper face channeled to provide an annular external seat for a packing ring 34 of brass or other suitable material. Engaging against the lowermost of these washers is the sleeve portion 35 of a piston, indicated as a whole by the numeral 36. The upper end of this sleeve portion is cut away to provide a seat for one of the packing rings 34. The under face of the upper portion of the piston, which is formed integrally with this sleeve, is channeled to provide a seat for a brass packing ring 37. A washer 38, forming the intermediate section of the piston, engages the packing ring and a terminal section 39 of the piston engages this washer and is channeled to receive another packing ring 40. The lower end of the plunger is threaded to receive a nut 41 which clamps the various parts of the piston 36 and of the piston 42 formed by the washers 33 and

packing rings 34, together. This plunger 32 is so proportioned that when its lower end rests upon the cap 28 its upper end will be somewhat below the lower end of the valve stem 17 when the valve 18 is closed. 70

Before describing the application and operation of the valve, I wish to direct attention to the fact that the opening or port 43 surrounded by the nipple 25 constitutes the live steam opening of the valve and the opening 44 surrounded by the nipple 13 constitutes the steam outlet of the valve, the opening 29 constituting means for admitting either steam or air under pressure to operate the compound pistons 36 and 42 to cause 80 opening of the valve 18 when desired, independent of the normal automatic operation of the valve. 75

In Figs. 3 and 4 I have illustrated the manner of applying my improved valve to a 85 locomotive engine of the compound type, in which 45 indicates the high pressure engine, 46 the low pressure engine and 47 a conduit for supplying live steam to the high pressure cylinder. Suitable pipe fittings 48 connect at one end to the nipple 25 and at the other end communicate with the conduit 47, while pipe fittings 50 establish communication between the port 44 of the casing and the exhaust passage leading from the high 95 pressure cylinder to the low pressure cylinder. A pipe 49 is led from the port 29 to any suitable source of compressed fluid, such as the main reservoir of the air brake system or the steam boiler, a manually controlled operating valve 50' being interposed in this pipe within the locomotive cab and normally kept closed. 100

In describing the operation of my improved valve, I will assume that the engine is stationary and that as a result there is no steam in the cylinders or in the conduit 47. Under these conditions, fluid pressure will be equal against opposite sides of the valve 18 and the spring 22 will hold 110 the valve open. When by the usual gradual opening of the throttle steam is admitted to the conduit 47 and so to the high pressure cylinder 45 to start the engine, a portion of this live steam will pass through the pipe 115 48 to the valve casing, escaping through the port 44 to the receiver pipe or passage leading from the high pressure to the low pressure cylinder. As the engine starts under steam pressure from the high pressure cylinder, the low pressure cylinder will take steam with the result that the pressure in the valve casing below the valve 18 will be suddenly reduced to such an extent that the unbalanced pressure of live steam above the 120 valve will close it against the action of the spring 22. Whether or not the valve then remains closed will depend upon running conditions. 125

At this point it should be noted, that due 130

to the difference in areas of the cylinders and due to the fact that the steam supplied to the low pressure cylinder is that exhausted from the high pressure cylinder, the 5 relative steam pressures in the live steam conduit 47 and in the exhaust passage between the high and low pressure cylinders, which is the relative steam pressure at opposite sides of the valve 18, will bear a constant 10 ratio to each other, that of the exhaust passage being a predetermined fraction of that in the conduit 47. For instance, to increase the steam pressure in the exhaust passage a pound, it may be necessary 15 to increase the live steam pressure in the conduit 47 four pounds. It will therefore be obvious that in starting the engine, steam pressure will be brought up in the live steam passage at a much faster rate than 20 in the exhaust conduit.

Under running conditions the pressure in the high pressure cylinder and the pressure in the low pressure cylinder will bear a certain definite ratio to each other and if the 25 pressure in the high pressure cylinder is from any cause reduced, the pressure in the low pressure cylinder will, of course, be reduced in accordance with such ratio. The spring 22 is capable of exerting a predetermined 30 constant degree of pressure against the valve tending to open the same, and this predetermined degree of pressure to be exerted by the spring is such that when the pressure against the upper side of the 35 valve, or in other words, the pressure in the high pressure cylinder is reduced to a predetermined degree, the pressure, in ratio, in the low pressure cylinder plus the pressure exerted by the spring will more than balance 40 the said pressure against the upper side of the valve and the valve will open. For example, if it is desired that live steam be admitted to the low pressure cylinder upon reduction of pressure in the high pressure 45 cylinder to 100 pounds, and assuming that with such a degree of pressure in the high pressure cylinder there is a pressure of 20 pounds in the low pressure cylinder, a spring will be provided which will exert 50 a pressure of approximately 85 pounds against the valve tending to open the valve; so that, when under running conditions the pressure in the high pressure cylinder falls to 100 pounds, the combined pressure of 55 the spring and the back pressure of the steam in the low pressure cylinder will result in automatic opening of the valve. Of course, so long as the pressure in the high pressure cylinder is above the predetermined 60 minimum the valve will remain closed unless it is opened through admission of fluid under pressure beneath the plunger 36.

The strength of the spring 22 is to be determined by the high cylinder pressure at 65 which the valve 18 is to open. Customarily,

the pressure in the two cylinders is at a ratio of 4 to 1, so that when the high cylinders are working under 200 pounds pressure the low cylinders and receiver pipe will be carrying 50 pounds pressure. If the high cylinder 70 pressure should fall to 95 pounds, the low cylinder pressure would drop to approximately 25 pounds and would be ineffective but if the spring exerts a pressure of 75 pounds, the high cylinder pressure will be 75 overcome by the spring and the low cylinder pressure so that the valve will be opened and the low cylinder prevented from becoming a dead element. In starting, the valve remains open until the pressure built up in 80 the high cylinder exceeds that built up in the low cylinder plus that exerted by the spring, when it closes. Actual use of my device has demonstrated that there is no unfavorable reaction on the high pressure 85 engine, but on the contrary, the engine is balanced and there is no slipping of the drivers. The increased efficiency of the low pressure engine more than offsets the decreased efficiency of the high pressure engine. 90

By supplying compressed air from the main reservoir of the air brake system or live steam under full boiler pressure through the pipe 49, the engineer may, at any time 95 he desires, cause upward movement of the plunger 32 and opening of the valve 18 to supply live steam to the low pressure cylinder. This will be done if, for any reason, the engine has had its speed reduced on account of low steam pressure so that it is about to stall, or under emergency conditions as for example, when increased load is imposed as on an up grade. 100

Having thus described the invention, what 105 is claimed as new is:

1. An automatic starting and regulating valve for compound steam engines comprising a casing having means whereby the same may be connected to the live steam duct of 110 a compound steam engine and provided intermediate its ends with a valve seat and a valve thereby forming a live steam chamber between said valve and said connecting means, said casing being provided with 115 means whereby the same may be connected to the passage between the high and low pressure cylinders of a compound steam engine, and spring means assisted by the steam pressure in the passage between the high 120 and low pressure cylinders for opening the valve against the pressure of the live steam in said chamber when the pressure of the live steam in said chamber drops below the combined pressure of said spring means and 125 the steam within said passage.

2. An automatic starting and regulating valve for compound steam engines comprising a casing having means whereby the same may be connected to the live steam duct of 130

a compound steam engine and provided intermediate its ends with a valve seat and a valve thereby forming a live steam chamber between said valve and said connecting means, one side of said casing being provided with means whereby the same may be connected to the passage between the high and low pressure cylinders of a compound steam engine, spring means assisted by the steam pressure in the passage between the high and low pressure cylinders for opening the valve against the pressure of the live steam in said chamber when the pressure of the live steam in said chamber drops below the combined pressure of said spring means and the steam within said passage, and a fluid pressure operated plunger carried by said casing in longitudinal alinement with said valve for opening said valve irrespective of the steam pressures.

3. The combination with a compound steam engine having high and low pressure cylinders with an exhaust passage connecting the high pressure cylinder with the intake of the low pressure cylinder, of a live steam duct to the high pressure cylinder, means connecting the exhaust passage and said duct and including a check valve closing in the direction of live steam flow and spring actuated toward the open position, whereby the high pressure cylinder exhaust assisted by the spring tension opens the valve to feed live steam to the low pressure cylinder when the steam pressure drops below a predetermined degree, and manually controlled means for opening said valve irrespective of the steam pressures.

In testimony whereof I affix my signature.

JAMES B. VERNON. [L.S.]
